UNITED STATES PATENT OFFICE.

WILLIAM H. SHARPE, OF LAKESIDE, OHIO, ASSIGNOR TO WESTERN ELECTRIC COMPANY, INCORPORATED, OF NEW YORK, N. Y., A CORPORATION OF NEW YORK.

ELECTRICAL SWITCHING DEVICE.

1,412,372.

Specification of Letters Patent. Patented Apr. 11, 1922.

Application filed May 5, 1920. Serial No. 378,972.

To all whom it may concern:

Be it known that I, WILLIAM H. SHARPE, a citizen of the United States, residing at Lakewood, in the county of Cuyahoga, State 5 of Ohio, have invented certain new and useful Improvements in Electrical Switching Devices, of which the following is a full, clear, concise, and exact description.

This invention relates in general to electrical switching devices and particularly to switching keys of the plunger type.

The invention is particularly useful in connection with automatic telephone systems where keys of this type are used for 15 selecting trunk lines at toll stations. With the keys ordinarily in use, when depressed, contacts are made which start the selecting apparatus. If the key does not happen to lock and returns to its normal position the 20 selecting apparatus halts without completing the proper connection.

The object of the invention is to provide a group of keys, positive in action and simple in construction.

25 To accomplish this object the invention in its preferred form provides a locking plunger type key which does not close its correlated contacts until it is locked in its depressed position. Another plunger key is 30 provided whose contacts do not "make" until depressed to a position where it operates to release the other key.

With this arrangement, the person operating the keys is certain that the keys have 35 performed their proper function.

The invention is shown in its preferred form in the drawing, in which Fig. 1 is a side view with portions of the locking apparatus cut away to show the construction 40 thereof, and Fig. 2 shows a cross-sectional view at the plane 2.

A supporting plate 1, having a bent up edge 3, is provided with apertures 29 and is fastened in any suitable manner to the underside of a shelf 4. Plunger rods 5 and 6 are adapted to move through the apertures 45 29 and are slidably guided at lower ends 7 and 8 respectively by guide members 9 which are fastened to the supporting plate 1 by means of screws 11. The plungers 5 and 6 are provided with coil springs 10 which tend to keep them in an elevated position. A slidable locking member 12 of U 50 shaped cross-section is supported by two supports 13. Slots 16 are provided in the

locking member 12 which cooperate with grooves 15 in the supports 13 to permit the locking member 12 to slide in the direction of its length. The supports 13 are fastened to the edge 3 of the supporting member 1, 60 by means of screws 14.

A cylindrical cam 17 is fastened on the shank of the plunger 5 and cooperates with a roller 19 supported crosswise of the locking member 12. A conical cam 18, supported on the shank of the plunger 6 cooperates with a roller 20 supported crosswise of the locking member 12. A strip 21 of slightly elastic material is fastened between the cams 17 and 18 and the edge 3 to absorb the shock 70 when the cams 17 and 18 are suddenly released.

A stiff contact spring member 22 mounted on the supporting plate 1 by means of a flange 24 is adapted to bear against a roller 75 30 which is supported crosswise of the locking member 12 and tends to pull the rollers 19 and 20 against the cams 17 and 18 respectively. A contact member 23 is provided to engage the spring member 22 when 80 released and is suitably supported with the spring member 22 on the flange 24. A bank of springs 25 may be supported on the flange 26 of the guide member 9 and may be operated in the usual manner by a conical cam 85 27. The key buttons 28, of any suitable form, may be fastened to the tops of the plungers 5 and 6 for the purpose of depressing the same.

When the plunger 5 is depressed, the top 90 of the cam 17 drops below the roller 19. The locking member 12, under the influence of the spring member 22, then slides to the right and the roller 19 locks the plunger 5 in its depressed position. Contacts 22 and 95 23 then engage to close an electrical circuit. To release the plunger 5, plunger 6 is depressed and the conical cam 18 forces the roller 20 to move the locking member 12 to the left whereupon the cam 17 being released, the plunger 5 rises to its normal position. Simultaneously, the spring contact members 25 contact, under the influence of the cam 27 and the contact between springs 22 and 23 is broken.

105

What is claimed is:

1. In a key assembly, a plurality of manually operable members, locking means for one of said members, means associated with said member to prevent the operation of 110

said locking means when said member is not operated, means associated with another of said members to restore the locking means, and circuit controlling means operable by 5 the locking means.

2. In a key assembly, a plurality of plunger keys, locking means, means to operate said locking means, means associated with one plunger key to prevent the operation of 10 said locking means when the plunger key is not depressed, means associated with another plunger key to restore the locking means, and circuit controlling means operable by the locking means.

15 3. In a key assembly, a locking plunger key, a non-locking plunger key, locking means for the locking plunger key, restoring means operated by said non-locking key to release said locking means, contact members operable by said locking means, and means associated with the locking plunger key normally preventing the operation of 20 the contact members by said locking means.

4. In a key assembly, a plurality of plunger rods, an end-wise slidable locking member, a spring contact member tending to produce a sliding motion in the said locking member, a cylindrical cam supported on 25 one of said plunger rods preventing such 30 sliding motion when the plunger is not depressed, a conical cam supported by another of said plunger rods to return the locking member to its normal position, and a contact member to contact with the said 35 spring contact member.

5. In a key assembly, a plurality of plunger rods, an end-wise slidable locking member cooperative therewith, a spring contact member to operate said locking member, a cylindrical cam fastened on one of the said plungers and adapted to release the said locking member and lock the said plunger in a depressed position, and a conical cam fastened on another of said plungers to return the 40 said locking member to its normal position. 45

6. In a key assembly, a supporting plate of L shaped cross-section, provided with apertures, a pair of plunger rods slidable through such apertures, a guide member for each said plunger rod and supported by the 50 supporting plate, a cylindrical cam fastened on one of said plunger rods, a conical cam fastened on the other of said plunger rods, coil springs on the plunger rods tending to keep the rods in an elevated position, a locking member of U shaped cross-section 55 slidable supported on the supporting plate and having portions cut away to permit the passage of the plunger rods therethrough, roller members supported by the U shaped 60 locking member and cooperative with the said cams, a spring contact member tending to press the roller members against the said cams, and contact means for said spring member. 65

In witness whereof, I hereunto subscribe my name this 23rd day of April, A. D., 1920.

W. H. SHARPE.
